UNITED STATES PATENT OFFICE.

ALVA L. KITSELMAN, OF MUNCIE, INDIANA.

WIRE-FABRIC-MAKING MACHINE.

SPECIFICATION forming part of Letters Patent No. 787,457, dated April 18, 1905.

Application filed December 24, 1903. Serial No. 186,497.

To all whom it may concern:

Be it known that I, ALVA L. KITSELMAN, a citizen of the United States, residing at Muncie, in the county of Delaware and State of Indiana, have invented a new and useful Wire-Fabric-Making Machine, of which the following is a specification.

This invention relates to an improved wire-fabric-making machine of that type disclosed in Patent No. 745,072 to W. N. Parrish, dated November 24, 1903. This type of machine is designed with special reference to the manufacture of wire fencing, and is characterized by provision for drawing a series of parallel line-wires from one or more spools, a plurality of devices for forming loops in the line-wires, provision for passing stay-wires through the loops, and means for operating the looping devices in a manner to permit the looped portions of the line-wires to be withdrawn from said devices and drawn out by the pull on the line-wires to form twists constituting connections between the line and stay wires. Auxiliary to this organization are guides for the stay-wires, these guides being in the form of grooves for directing the stay-wires as they are fed or "shot" through the loops, the open side of these guide-grooves being closed by a gate or apron movable away from the grooves when the withdrawal of the stay-wires from the latter is necessary. In the practical operation of this machine I have discovered certain defects, to the correction of which my present invention is directed. Most of these defects arise in consequence of an imperfection in the construction of the loopers. These loopers comprise rotary heads, each of which includes a loop-forming device or hook in the outer or end face of which is formed a channel or guide through which the stay-wire is led in order to effect its passage through a line-wire loop formed on the hook. When the stay-wire is fed forward, this channel in the outer face of the hook is aligned with the guide-grooves, which, as has been explained, are closed by the gate or apron. By reason of the fact that the line-wire loop is formed around the hook the gate must be cut away opposite the hook to prevent interference with the line-wire, and as a conse-

quence the open side of the channel in the outer face of the hook is unguarded. If, therefore, as sometimes happens, the advancing end of the stay-wire is deflected in passing through the hook, it is permitted to escape 55 through the open side of the channel instead of passing on in a direct line to the next hook. When an accident of this character occurs, the machine must be stopped and the stay-wire drawn back and reinserted by hand. 60 In fact, it is ordinarily necessary to complete by hand the weaving in of the new stay-wire, since any considerable feed of the deflected stay-wire after its escape from the hook will have materially advanced the positions of the 65 loop-forming devices. Another and more serious result of the stated construction of the loop-forming hook is that the turning of the hook from a horizontal to a vertical position for the purpose of releasing the loop deflects 70 that portion of the stay-wire passing through the hook, this deflection being formed between sharp artificial bends formed in the stay-wire at the opposite ends of the hook. Since the loop of the line-wire encircles the deflected portion of the stay-wire, said loop when drawn out by the strain on the line-wire after the release of the loop from the hook causes the twist to extend the entire distance between the artificial bends in the stay-wire, and this connection of the two wires being of abnormal or 75 artificial length and standing at an angle to both the stay and line wires causes material distortion of the fence when the latter is stretched up—that is to say, the drawing taut 80 of the line-wires in stretching up the fence causes these intertwined portions or connections of the wires to be drawn into line with the line-wires, and as the line-wires of a fence are different distances apart and as all of these 85 angular connections or twists are of the same length those portions of the stay-wires extending between the line-wires will be disposed at various angles. The described action of the looper, in addition to forming objectionable artificial bends in the stay-wires, 90 causes the galvanizing or protective coating on the latter to be scraped, skinned, or peeled off at the bends, and the wires are therefore weakened by rust upon exposure to the 95 100

weather. Not only that, but the formation of the stay-wire channel in the outer face of the hook necessitates the withdrawal of the stay-wire from the hook in a direction at right angles to that in which the strain is applied—that is to say, the stay-wire must move out of the channel in a horizontal direction, while the strain which effects this removal is vertically directed by the pull on the line-wire. 5 10 This results in impeding the operation of the machine, augments the mutilation of the wire, and accentuates the artificial bends in the stay-wire.

To the elimination of these objectionable 15 characteristics my invention has for its object the improvement of the loopers and the stay-wire-guiding means in order to provide a continuously-closed guide for the stay-wire and to provide for the withdrawal of the stay 20 and line wires from the loopers without mutilating or producing artificial bends in the stay-wire and without causing the latter to present undue resistance to the withdrawal of the wires from the looping-hooks.

25 To the accomplishment of these objects and others subordinate thereto, as will more fully appear, the preferred embodiment of the invention embraces that construction and arrangement of parts to be hereinafter described, illustrated in the accompanying drawings, and succinctly defined in the appended 30 claims.

In said drawings, Figure 1 is a sectional elevation of so much of a fence-machine as is necessary to the illustration of my invention, this 35 view embracing a portion of the machine-frame, a looping device, and the connections whereby said looping device is rotated and the hook or looper thereof reciprocated. Fig. 40 2 is a horizontal section through one of the looping devices and its mounting and showing certain of the machine elements in plan. Fig. 3 is a face view of a looping device with a line-wire extending through the hook. Fig. 45 4 is a horizontal section on the line 4 4 of Fig. 3, the hook or looper being shown in elevation. Fig. 5 is a view similar to Fig. 4 with the hook drawn back. Fig. 6 is a view similar to Fig. 3, showing the looping device after 50 it has made one-half rotation in the direction of the arrow to form a loop in the line-wire. Fig. 7 is a horizontal section on the line 7 7 of Fig. 6, showing the stay-wire shot through the loop in the line-wire. Fig. 8 is a vertical 55 section on the line 8 8 of Fig. 6. Fig. 9 is a horizontal section similar to Fig. 7, but showing the hook projected to withdraw the stay-wire from the guides preparatory to the turning of the hook in a reverse direction to release the interlocked wires therefrom. Fig. 60 10 is a view similar to Fig. 9, but showing the looper after it has made a quarter-turn in the direction indicated by the arrow from the position shown in Fig. 9 to effect the release of 65 the wires from the hook. Figs. 11, 12, and

13 are diagrammatic views designed to illustrate the manner in which the wires are released from the hook, Fig. 11 being a face view of the hook and wires positioned as in Fig. 9, Fig. 12 being a similar view after one-eighth reverse rotation of the hook, and Fig. 13 showing the hook after it has moved to a vertical position from the position shown in Fig. 12 to permit the complete withdrawal of the interlocked wires. Fig. 14 is a view of 70 75 the connection between the line and stay wires after said wires have been intertwined by the pull on the line-wire immediately subsequent to the release of the wires from the hook, the position of the hook being indicated in this 80 figure. Fig. 15 is a detail section on the line 15 15 of Fig. 6, and Fig. 16 is an edge view of the detachable face-plate of a looper-head.

Like numerals of reference are employed to designate corresponding parts throughout the 85 several views.

Between the opposite sides of the machine-frame (not illustrated) extends a supporting member or rail 1, provided at intervals with bearing-sleeves 2 for the reception of looping 90 devices, each of which comprises a rotary head 3, having a reduced spindle 4, journaled in the bearing-sleeve 2, and inclosing the cylindrical shank 5 of a hook or looper 6, preferably rectangular in form and somewhat narrower than the shank, in order to bring one side face of the hook substantially in a line with the axis of the shank. This angular contour of the hook is designed to compel the rotation of the hook and head in unison, since the head 3 is provided with a detachable face-plate 7, formed with an opening or socket 8 for the reception of the hook and corresponding in contour therewith. (See Figs. 3 and 4.) In rear of the face-plate 7 the head 3 is formed 100 with a cavity 9, extending from the opposite sides of an inward extension 8^a of the socket 8. Opposite the ends of this concavity the face-plate 7 is pierced by openings 10 and 11 preferably, though not necessarily, of circular 105 form, as shown in Fig. 3, and connected with the socket 8 by comparatively narrow throats 12 and 13, it being understood that in certain modified constructions the structure of the head as a whole will be substantially that 110 shown and described, except that the face portion thereof instead of being in the form of a separate plate would be an integral part of the head structure. Above and below the opposite ends of the socket 8 in the normal position of the head (see Fig. 3) the face-plate 7 is formed with cam lugs or guides 14 and 15, which rise from the plane of the outer face of the plate to the plane of the outer face of the hook or looper 6 when the latter is drawn back 115 or retracted to the position indicated in Fig. 5, the purpose of these projections 14 and 15 being to facilitate the rotation of the head without interference from the line-wire, as will more 120 appear. Normally the hook is disposed 125 130

in a horizontal position, as shown in Fig. 3, with the cavity 9 in the head disposed vertically. In this position of the looping device the hook is in its projected position, as seen 5 in Fig. 4, with its opening located at the right-hand end thereof. In this position the hook receives the line-wire *a*, which in the machine now under discussion occupies a substantially vertical position opposite the looper. The 10 manner in which the line-wire is inserted in the hook, as shown in Figs. 3 and 4, is immaterial; but it may be remarked in passing that the wire *a* is passed upwardly through a guide 16, (see Fig. 2,) which is shifted laterally by 15 suitable mechanism--as, for instance, a rocker-arm 17 and a cam 18--to move the line-wire into the opening 20 of the hook when said hook has been moved to the position shown in Figs. 3 and 4. The line-wire having been 20 positioned in the hook, as shown, said hook is drawn back or retracted for the purpose of drawing a portion of the line-wire into the cavity of the head, as shown in Fig. 5, the openings 10 and 11 and the throats 12 25 and 13 facilitating this manipulation of the wire. The looper is next rotated by mechanism to be described through one hundred and eighty degrees--that is to say, the head and hook moving in unison are turned one-half of 30 a complete rotation to cause the line-wire to be looped around the looping-finger 21 of the hook in a manner well understood by those skilled in the art. During this movement of the head the looping of the line-wire is facilitated by the cam-lugs 14 and 15, which ride under those portions of the line-wire disposed above and below the hook, thus urging the main portions of the wire outwardly from the face of the looper-head to permit the ends of 35 40 the hook to pass freely under the wire as its position is reversed. The looper will then have reached the position indicated in Figs. 6 and 7, and the line-wire loop will be ready to receive the stay-wire. The stay-wire *b* is fed 45 across the machine from one side thereof and is designed to pass through the line-wire loops formed on the several loopers of the series. Necessarily the stay-wire must be guided, and for reasons which have heretofore been explained this guide must be substantially continuous. To provide such guiding means, each of the looper-heads is provided in its outer face with a diametrical guide-groove 22, extending from its periphery to the socket 8, 50 55 the grooves in the several heads being in alinement with each other and with intermediate guide-grooves 23, formed in the outer faces of fixed guide-blocks 24, secured to the support or rail 1 intermediate of the heads. 60 (See Fig. 2.)

We now come to consider a feature of primary importance, since it constitutes the leading characteristic of the present invention. In one side face of each hook--to wit, that 65 side face 25 which in the present construc-

tion is located substantially in the plane of the twister-axis and which when the line-wire loop has been formed constitutes the upper or top face of the hook--is formed a stay-wire channel 26, (see Figs. 7 and 8,) which is in alinement with the guide-grooves 22 in the face of the head. Particular attention is directed to the location of this channel 26, for the reason that to the novel location of this channel may be attributed the elimination of all of those 70 characteristics which have heretofore been pointed out as objectionable in this type of machine. Heretofore the stay-wire channel in the hook has been formed in the outer or front face thereof, and, as explained, it has been 75 impossible to guard said channel, for the reason that the gate or apron utilized to close the open sides of the guide-grooves 22 and 23 cannot be brought into close relation with the outer face of the hook, around which the line-wire is looped. In my construction, on the contrary, the channel 26, being formed in the side face of the hook, is closed by the upper wall of the socket 8 in the head when the hook is in position to receive the stay-wire. 80 It follows, therefore, that as the gate or apron 27 (shown in Figs. 1 and 2) is utilized to close the open sides of the guide-grooves 22 and 23 before the stay-wire is shot across the machine and as the channels in the hooks are likewise 85 closed by the walls of the sockets 8 the stay-wire will be provided with a continuous closed guide, from which it cannot possibly escape during its rapid passage across the machine and through the several loops of the line-wires. Attention is directed to the fact that while the continuity of the channel-closing wall of the socket 8 in the head is broken by the throat 13 said throat is occupied by the 90 95 loop of the line-wire, so that the escape of the stay-wire from its guide is absolutely impossible. The stay-wire having been shot through the loops of the line-wires, the hooks are now projected to the position indicated in Fig. 9, which operation serves to withdraw the stay-wire *b* from the guide-grooves 22 and 23, it being obvious, of course, that the gate 27 will be previously operated to open the outer sides of the grooves. The looping devices will now 100 105 have completed their functions as loopers for the line-wires and as guides for the stay-wire and will be ready to make a quarter-turn in the reverse direction (indicated by the arrow in Fig. 9) to effect the release of the wires. We may now appreciate a far greater advantage 110 for the novel location of the stay-wire channels 26 in the looper-hooks than the mere prevention of the accidental deflection of the stay-wire in its passage across the machine. By reference to Figs. 11, 12, and 13 the positions assumed by the parts during the release 115 of the wires may be noted. As the hook begins to rotate from the horizontal position (shown in Fig. 9) to the vertical position (shown in Fig. 10) the stay-wire will be sustained and 120 125 130

perhaps raised slightly by the left-hand end of the hook or the looping-finger thereof, and the channeled face of the hook will recede from the stay-wire without opposition from either wall of the channel and without producing artificial bends in the stay-wire. At the same time the end of the looping-finger of the hook will be withdrawn from the loop, so that as the hook reaches its vertical position the wires will have been entirely released, and the pull on the line-wire will now draw up the loop with sufficient force to effect the intertwisting of those portions of the two wires located between the opposite ends of the line-wire loop. The bending of the stay-wire necessary to effect the intertwist is what may be termed a "natural" or "normal" bend, produced merely by the strain upon the line-wire as distinguished from artificial bends produced heretofore by the hook and separated by an abnormally-long deflected portion of the stay-wire. When the artificial bends referred to are formed in the stay-wire by the machine, that portion of the wire extending between these bends is disposed at an angle more or less acute with respect to the line-wire. Therefore when the wires are finally released from the hook the pull upon the line-wire causes the opposite end portions of the loop therein to slide along the deflected portions of the stay-wire until arrested by the artificial bends in the latter. When thus arrested, the intertwisting of the wires is effected; but this intertwined portion or connection instead of being of normal length, as when produced by a machine embodying my improvement, is of a length abnormal and highly objectionable, for reasons hereinbefore stated.

The mechanism for effecting the described movement of the parts may be of ordinary form and constitutes no part of my present invention. It may be stated, however, that the looper-heads are synchronously operated by a rack 28, (see Figs. 1 and 2,) supported as shown and meshing with a pinion 29, fixed to the rear end of each looper-spindle 4. The synchronous retraction and projection of the looper-hooks is effected by means of oscillatory levers 30, operated by cams 31 and engaging channel-blocks 32, secured to the outer ends of the looper-shanks 5. (See Fig. 2.)

By way of summary, attention may now be directed to the fact that to the attainment of the specified objects of the invention the stay-wire channel in the looper is disposed to permit the free withdrawal of the stay-wire therefrom as the looper is moved, this withdrawal being effected in a lateral direction with respect to the axis of the looper or toward the advanced portion of the line-wire, which latter being subjected to an endwise strain effects the removal of the wires as the latter are released from the loopers by the reverse move-

ment thereof. Furthermore, that such location of the stay-wire channel in the looper causes the closing of the open side of the channel by one wall of the looper-socket through the movement of the looper as the latter is retracted and that as the stay-wire guide-grooves intermediate of the loopers are closed by the apron a continuously-guarded guide will be provided for the stay-wire.

It is thought that from the foregoing the novel construction of the machine and the advantages accruing therefrom will be clearly comprehended; but while the present embodiment of the invention is believed at this time to be preferable I desire to be distinctly understood as reserving the right to effect such changes, modifications, and variations of the illustrated structure as may fall fairly within the scope of the protection prayed.

What I claim as new is:

1. A rotary looping device for connecting the line and stay wires of woven-wire fabric, comprising a head, and a line-wire looper having a stay-wire channel, one side of which opens in a lateral direction with respect to the axis of the device.

2. A rotary looping device, comprising a head, and a line-wire looper formed with a stay-wire channel disposed transversely thereof and having an open side through which the stay-wire may be withdrawn in a lateral direction with respect to the axis of the device.

3. A rotary looping device, comprising a head, and a line-wire looper having a stay-wire channel formed in its side face to permit the free withdrawal of the stay-wire.

4. A rotary looping device, comprising a head and a line-wire looper, said looper having the form of a hook provided at one side with a transverse stay-wire channel for the reception of a stay-wire disposed substantially at right angles to the line-wire and passed through the loop thereof, one side of the stay-wire channel opening toward the advanced portion of the line-wire at the beginning of the wire-releasing movement of the looper.

5. A rotary looping device, comprising a head and a coaxial line-wire looper provided with a stay-wire channel and means for effecting the following movement of the parts to wit, the retraction of the looper to draw the line-wire into the head, the turning of the head and looper in unison to form in the line-wire a loop through which the stay-wire is guided by the stay-wire channel, the projection of the looper to withdraw the wires from the head, and the reverse turning of the head and looper in unison to release the wires from the looper, the stay-wire channel being formed in that side of the looper which is uppermost at the beginning of the reverse or wire-releasing movement of the parts.

6. A rotary looping device, comprising a head and a relatively movable line-wire looper

having an open-sided stay-wire channel and means for closing the open side of said channel to prevent the lateral deflection of the stay-wire therethrough.

5 7. A rotary looping device, comprising a head and a relatively movable line-wire looper having an open-sided stay-wire channel, and means whereby the movement of the looper will effect the closing of the open side of said 10 channel.

8. A rotary looping device, comprising a head having a socket, and a relatively movable line-wire looper having an open-sided stay-wire channel opposed to a wall of the 15 socket in one position of the looper.

9. A rotary looping device, comprising a head formed with a socket, openings at opposite sides of the socket and narrow throats extending to the socket from said openings, 20 and a line-wire looper movable into the socket and having a stay-wire channel.

10. A rotary looping device, comprising a head formed with a socket, openings at opposite sides of the socket and narrow throats 25 extending to the socket from said openings, and a line-wire looper movable into the socket and having a stay-wire channel in its side face.

11. A rotary looping device, comprising a head, a line-wire looper having a stay-wire 30 channel, and projections on the head to facilitate the passage of the looper under the line-wire when the twister is turned to form a line-wire loop.

12. A rotary looping device, comprising a 35 head formed with a socket, openings at opposite sides thereof, narrow throats extending to the socket from the openings, and cam-lugs at the opposite sides of the socket and adjacent to the opposite ends thereof, and a 40 line-wire looper movable in the socket of the head and having a stay-wire channel in its side face.

13. A rotary looping device, comprising a head and a line-wire looper, said head being 45 composed of a body part having a concavity in its end, and a face-plate detachably secured to the end of said body part and having a socket and openings, the latter extending to the socket and located opposite the concavity, 50 and said looper being movable in the socket and provided with a stay-wire channel.

14. A rotary looping device, comprising a head having a detachable face-plate formed

with a socket, and a line-wire looper movable in said socket and having a stay-wire channel. 55

15. A rotary looping device, comprising a head and a line-wire looper having a stay-wire channel formed in its side face and substantially intersecting the axis of the twister.

16. A rotary looping device, comprising a 60 head, and a line-wire looper having a shank coaxial with the head and a stay-wire channel formed in the side face of the looper and substantially intersecting the axis of the shank.

17. A rotary looping device, comprising a 65 head and a line-wire looper, said elements having stay-wire grooves or channels opening in different directions, one of said grooves or channels being formed in a side face of the looper. 70

18. A rotary looping device, comprising a head having a stay-wire groove or channel, and a line-wire looper having a stay-wire groove or channel the open side of which is disposed in a plane substantially at right angles to the plane of the open side of the groove or channel in the head. 75

19. In a machine of the class described, the combination with a support, and a series of 80 rotary looping devices each including a line-wire looper; of a stay-wire groove or channel extending from end to end of the series of twisters and formed in part in the loopers, and mechanism whereby all side openings of 85 said groove or channel will be closed to prevent the lateral escape of the advancing end of the stay-wire. 85

20. In a machine of the character described, the combination with a support, and a series 90 of rotary looping devices each including a line-wire looper; of a stay-wire groove or channel extending from end to end of the series of twisters, a gate for closing the open side of said groove intermediate of the loopers, and means whereby those portions of the groove 95 or channel which are formed in the loopers will be guarded to prevent the deflection of the stay-wire in its passage through said loopers.

In testimony that I claim the foregoing as 100 my own I have hereto affixed my signature in the presence of two witnesses.

ALVA L. KITSELMAN.
